UNITED STATES PATENT OFFICE

CLARENCE D. COULTER, OF LOS ANGELES, CALIFORNIA, ASSIGNOR TO SOUTHWESTERN ENGINEERING CORPORATION, OF LOS ANGELES, CALIFORNIA, A CORPORATION OF CALIFORNIA

ABSORPTION PROCESS

Application filed August 16, 1928. Serial No. 129,324.

This invention relates to absorption systems, such for instance as are used for removing gasoline or other light hydrocarbons from natural gas. Although, as will be readily realized, the invention is not restricted to the absorption and separation of gasoline from natural gas, being applicable generally to the absorption of any vapors or mist carried in any gas, yet the invention will be 10 most readily understood from a detailed explanation of its application to natural gas.

For some time past it has been the practice to separate gasoline or other light hydrocarbons from natural gas by an absorption 15 process; the processes consisting mainly of bringing the vapor laden gas into contact with a heavier hydrocarbon absorbing oil, whereby the oil absorbs the light hydrocarbons; and then separating the light hydrocarbons from the heavier absorbing oil by fractional distillation and condensation.

In practicing such processes there have been certain difficulties encountered. Natural gas as it comes from a well carries in 25 vapor or mist form not only a certain quantity of hydrocarbons that can be generally denoted gasoline; but also carries a quantity of hydrocarbons lighter than gasoline (having a lower boiling point than gasoline). Although in strict theory there may be no sharp dividing line, as regards vaporizing point, between what is termed gasoline and lighter hydrocarbons that are not regarded as fixed 30 gases; yet, for practical purposes, there are arbitrary dividing lines between these three classes of hydrocarbons in natural gas. The gasoline in the natural gas may be carried either in vapor or mist form; the lighter hydrocarbons may be in vapor form and may 35 be condensable at least to a certain extent at normal atmospheric temperature or a little lower; while the remainder of the natural gas, ordinarily regarded as fixed gas, is not condensable at any usual atmospheric temperature or a temperature somewhat lower.

In absorbing the liquefiable hydrocarbons into an absorbing oil it has been found difficult to maintain conditions of temperature 50 that will cause the absorption of the desired

gasolines without a concomitant absorption of a considerable quantity of lighter hydrocarbons. These lighter hydrocarbons are not desired in the final product, being vaporizable at too low a temperature; but a certain quantity of them is inevitably absorbed along with the gasolines and must later be separated from the gasolines. These lighter hydrocarbons are absorbed largely in 55 vaporous form; and they give to the laden or rich absorbing oil a comparatively high vapor pressure. It is one of the objects of this invention to provide a system wherein all the gasolines are absorbed but the quantity of such lighter hydrocarbons absorbed is substantially reduced, so as to reduce the vapor pressure of the rich absorbing oil and so as to reduce the quantity of such lighter hydrocarbons that must later in the system 60 be separated from the gasolines. It is also an object of this invention to provide a system wherein the absorbing oil, the gasolines, and the small quantity of lighter hydrocarbons are cleanly separated each from the others; so that all the gasolines are finally 65 recovered clean and free from both the absorbing oil and the lighter hydrocarbons, and the absorbing oil is cleaned of all its absorbed hydrocarbons to be used again in absorption. In separating the absorbed hydrocarbons from the absorbing oil it has been found difficult to maintain such conditions of temperature and pressure as will vaporize 70 all of the gasoline and not at the same time vaporize off a part of the absorbing oil. It is an object of this invention to maintain such control conditions as will cause a clean separation of the gasoline and lighter hydrocarbons from the absorbing oil; so that the absorbing oil is left clean and so that the vapors 75 then to be dealt with in the system contain no vapors of the absorbing oil. And finally, it is an object to maintain such control conditions that the final separation of the gasolines from the lighter hydrocarbons is clean.

The method and apparatus by which I accomplish these objects, and which are typical of my invention, are set forth in typical and preferred form in the following detailed 80 85 90 95 100

specification and illustrated in the accompanying drawings, in which:

Fig. 1 is a diagrammatic flow sheet of the system;

Fig. 2 is a plan of that part of the apparatus which lends itself readily to being assembled upon a common base;

Fig. 3 is a side elevation of the apparatus shown in Fig. 2;

Fig. 4 is an end elevation of the apparatus shown in Fig. 2 (from the left hand of Fig. 2) parts being broken away and shown in section;

Fig. 5 is a sectional elevation taken as indicated by the line 5—5 on Fig. 2;

Fig. 6 is a detailed section of the reflux tower, said section being taken as indicated by line 6—6 on Fig. 4;

Fig. 7 is a further enlarged detailed section taken on line 7—7 of Fig. 6;

Fig. 8 is a fragmentary perspective of a portion of the apparatus shown in Figs. 6 and 7;

Fig. 9 is an enlarged central section showing the construction of the reflux tower, said section being taken as indicated by line 9—9 on Fig. 6; and

Fig. 10 is a vertical sectional view showing the structure and arrangement of a condenser used in the system.

It will be understood that there are various other objects of the invention in addition to those hereinbefore set forth; but such other objects will be best understood from the following detailed description. In this description, with the aid of the accompanying drawings, I go into some particular detail as to structure and operation of the system and its various parts; but it will be understood that I do this not for the purpose of necessarily limiting the invention to the particular details herein set out, but for the purpose of enabling the invention itself to be well and fully understood by way of a full and detailed description of one illustrative and practical manner of carrying the invention into effect.

In describing the method and apparatus, subject matter of this application, I shall first describe the flow of gases and liquids through the apparatus in general, having reference first for that purpose to the flow sheet of Fig. 1.

Gas containing condensable hydrocarbons is brought to the apparatus under any suitable pressure, say from five pounds per square inch above atmosphere or any desired higher pressure. This pressure may be obtained from the natural source or by use of a compressor plant. The rich gas is first brought through pipe 10 to a gas accumulator A, which may comprise a simple small tank in which any solid or liquid matter is dropped out of the gas, and the accumulated matter withdrawn through pipe 9. The gas then

passes through pipe 11 under control of valve 12 to a gas scrubber B¹ and a gas cooler B, where its temperature is preferably reduced to approximately 70° F. The cooling medium in this cooler is cold water introduced and taken away through water lines 13 and 14 which connect with main water lines 15 and 16. A compressor C may be connected into line 11 and this compressor may be used for raising the requisite pressure if the gas, as it flows to accumulator A, is not under sufficient pressure. The pressure used is that which will cause the gases to flow through the various apparatus elements, and particularly through the absorption tower D and maintain therein the best operating pressures for gasoline absorption. Thus, the operating pressure raised at compressor C may vary with different circumstances and in varying conditions, as is well understood. A typical pressure for absorption tower operation is about thirty pounds per square inch above atmosphere.

Cooler B is any suitable kind of heat exchanger, for instance, a tubular heat exchanger of one or more units. From this cooler the gas passes through pipe 17 to the bottom of absorption tower D, preferably of the bubble type. While I may use a tower of any type wherein the gas is brought into intimate contact with the absorbing oil or other medium, I prefer to use an apparatus of the gas bubbling type, such as is shown in the application of Raymond B. Millard, S. N. 709,811, filed April 29, 1924, entitled Bubble tower.

The gas passes through the absorption tower and out through the line 18 or 18^a where it may be put into storage or led directly to use or discharged to atmosphere. Dry gas from the absorption tower may pass through a tail gas accumulator A¹ similar to "A" for recovering any carried over absorption oil which can be introduced back into the weathering tank E by means of a trap A² and line A³. The back pressure valve 19 maintains a constant gas pressure on the absorber. The oil or other absorbing medium enters the top of the tower through line 20 at approximately 70° F., passes down through the tower where it comes into intimate contact with the rising gases, absorbs all liquids carried in suspension or in vaporous or mist form in the gases—mainly gasoline—and accumulates at 21 in the bottom of the tower. (Further details of structure and operation are given later.) This oil, with its load of gasoline, and hereinafter called rich oil, leaves the bottom of the tower through pipe 22 and goes to weathering tank E. Line 22 is controlled by valve 23 which in turn is controlled by the float mechanism 24, the function of this float controlled valve being to maintain in the bottom of the absorption tower a given depth of rich oil, and to feed the rich oil out of the

130

absorption tower to the weathering tank as additional rich oil accumulates in the bottom of the tower.

In the weathering tank the pressure may be reduced, if desired, by a pressure relieving valve 25 set at any desired pressure. If the pressure here is relieved to any extent, gases will come off through the relief valve and these gases may be discharged to atmosphere or back to suction of compressor C by line 25^a, or may be discharged to a gas line or storage, as desired. The function of the weathering tank, which is merely a plain tank, is to allow absorbed gases to separate and escape so as to further reduce the amount of light hydrocarbons in the absorbing oil and to provide a point of comparatively low pressure in the system where dephlegmator bottoms may be discharged under still pressure.

The rich oil, still cold, is then taken from the weathering tank through line 102 to pump F, known as the cold rich oil pump, which pump forces the oil through line 26 to a heat exchanger G, where the rich oil is heated by exchange of heat from hot oil, as will be described later. Heat exchanger G may be of any suitable structure as, for instance, of the shell and tube type.

From heat exchanger G the warmed rich oil, still under pump pressure from pump F, passes through line 27 to heater H, where it is heated to approximately 300° to 320° F., by steam. The steam for this heater is live, dry steam, preferably under a pressure of from 80 to 150 pounds per square inch, fed to the heater through pipe 28; and the water condensate is taken from heater H through line 29 and trap 30 to the water discharge line 31, which is a part of the water circulating system and leads to water cooling tower T.

The heated rich oil passes from heater H through line 32 into the top of an evaporator I, where the pressure is released to approximately fifteen pounds per square inch above atmosphere, and the absorbed gasoline and other light hydrocarbons are permitted to expand into vaporous form together with a small amount of absorbing oil. It will be understood that up to the time the rich oil reaches evaporator I it has been held under such pressure (pressure of pump F) as to hold down evaporation of the absorbed hydrocarbons, so that although the rich oil is heated to the stated temperature in heater H, full evaporation of the absorbed hydrocarbons does not take place until pressure is released in evaporator I. The oil pressure in heater H may be as high as fifty pounds per square inch, or more. The unevaporated oil falls to the bottom of the evaporator and stands in a body at 33, this oil being substantially freed from its former burden of light hydrocarbons. Most of the gasoline evapora-

tion is caused by release of pressure when the liquids enter the evaporator; but in order to cause complete and clean evaporation of the lighter hydrocarbons, live steam is admitted through line 33^a to the bottom of the evaporator to pass up through and agitate the oil body and to decrease the partial pressure on the oil for the purpose of more readily evaporating and releasing the light hydrocarbons. As a result, the light hydrocarbons are completely vaporized in the evaporator and these vapors pass off through line 34 to reflux tower J. Further details of operation in the evaporator are given later, particularly pointing out how the absorbed hydrocarbon vapors are here completely separated from the absorbing oil.

The hot lean oil from the bottom of evaporator I passes back through line 35 to heat exchanger G where it gives up a part of its heat to the cool rich oil that passes through that heat exchanger on its way to heater H, as before described. Leaving the bottom of heat exchanger G this oil, somewhat cooled but still warm, passes through line 36 to pump K, whence it is pumped through line 37 to the top of oil cooler L, where the temperature is reduced to approximately 70° F. Cooler L is supplied with water by lines 15^a and 16^a which connect into main water lines 15 and 16. Passing out of the bottom of oil cooler L through line 20, the cooled lean oil is forced, still under pump pressure, again into the top of the absorption tower, thus completing the circulation of the absorbing oil. The charge of absorbing oil is thus continuously used in the system and only needs replenishing as small losses occur. In the evaporator, a small quantity of absorbing oil is constantly vaporized, the temperature being kept high enough in the evaporator to insure evaporation of all the light hydrocarbons, even at the expense of evaporation of a small portion of the absorbing oil; but, as hereinafter explained, this portion of the absorbing oil is also put back into the system.

In order to regulate the withdrawal of hot lean oil from the bottom of evaporator I, so that a constant suitable quantity of oil is kept at all times in the bottom of the evaporator, a float mechanism 40 is provided in connection with the evaporator. This float mechanism, through controlling connections, diagrammatically indicated at 44, controls the steam supply through valve 45 to pump K. Pump K, as will be remembered, draws the oil from evaporator I through heat exchanger G.

Instead of passing lean oil directly from heat exchanger G to pump K, that lean oil may pass from the heat exchanger through pipe 36 and a by-pass line 41 to storage tank P; and then pump K may draw oil from that storage tank through line 42 and pipe 36, a valve 36^a in pipe 36 being closed. If this arrange-

ment is used, the float mechanism 40 controls a valve 43 on line 41, through the medium of connecting mechanism indicated diagrammatically at 44^a. In cases where emulsion tends to form in the absorption oil the tank 5 P acts as a settling tank for removing the water.

The mixed vapors coming off from evaporator I pass from the top of the evaporator 10 into the bottom of a dephlegmator consisting of a reflux tower J and a condenser or control section M. The details of structure and operation of this dephlegmator are explained hereinafter. The control section on condenser M is fed with water by lines 15^b and 16^b, connecting with the main water lines 15 and 16, and its function as hereinafter described is to control the temperature at which the vapors finally pass from the dephlegmator; the general function of the dephlegmator being to cause condensation of all vapors of the heavier oils and thoroughly to clean the hydrocarbon vapors (gasoline) so that no vapors except the desired gasoline 25 vapors pass to the condenser N. The final vapors pass through pipe 50 from reflux tower J to condenser N; and the condensate passes from condenser N through line 51 and its back pressure valve 52 to a separator O, 30 wherein the gasoline and the water are stratified. The gasoline vapors necessarily are admixed with a certain amount of water vapor on account of the introduction of steam into the bottom of evaporator I; and this 35 steam is not condensed, or not wholly condensed, in the dephlegmator. When the mixed vapors emerge from evaporator I they may typically be at a temperature of about 290° F.; and after passing through the dephlegmator they may typically come out to condenser N at about 180° to 210° F. In condenser N the temperature will be lowered to a point fairly well below the vaporizing temperature of any of the gasoline constituents, say to a temperature of 75° F., or, in practice, as low as possible with the cooling 45 water available. Typically a fairly low pressure, say a pressure of 5 to 30 pounds per square inch, is maintained on the evaporator, 50 the dephlegmator and the condenser; but if desired the pressures there may be still lower; the condenser may even be operated in such a manner as to create by suction a low pressure that will extend back to the evaporator, 55 but I prefer to evaporate and condense under pressure. The function of valve 52 is to maintain, by proper setting, the desired pressure in the condenser and back to the evaporator.

The water separated in separator O is 60 drawn off through line 53 and through a trap 54 and thence through line 55 into the bottom of cooling tower T, this water being cool enough that it does not have to be cooled in the tower. The refluxed and condensed 65 oils that are thrown down in reflux tower J

are drawn off from that tower through line 56 and through trap 57 and thence through line 58 to a cooler and thence either to the lean oil storage tank P or to weathering tank E. For instance, the oil line 58 may go to a coil, 70 indicated at 59, in the lower part of cooling tower T, where the refluxed oil is cooled, and then the oil may pass back by line 60 either to tank P or by branch line 60^a to weathering tank E. In either case, the refluxed absorbing oil is thus put back into the system; in one case at a point where the reflux oil does not pass through the absorption tower; in the other case (tank P) at a point where it then goes through the absorbing tower (by 80 way of the cooler L and the line 20). Where the reflux oil from reflux tower J is clean of all absorbed hydrocarbons it may be put back into tank P; but if under any circumstances the reflux oil should still contain a slight 85 amount of such hydrocarbons it may be put back into the system at a point (such as weathering tank E) where it joins the rich oil. Thus in any case the oil going to absorbing tower D is clean and has maximum 90 absorption qualities; and the fact that the reflux oil may retain a small amount of absorbed hydrocarbons has no final effect on the efficiency of the system, as it simply means the retention in the system of a small 95 fixed amount of absorbed hydrocarbons.

Gasoline taken off from separator O is passed through the pipe line 61 to a tank R from which the gasoline may be withdrawn from time to time as desired. The uncondensed lighter hydrocarbons pass from separator O to tank R by line 61^a. If it is desired to maintain on separator O and the tank R the same back pressure as is maintained on condenser N, a back pressure valve may be 100 installed at 62 on tank R.

The gasoline line 61 running from separator O to tank R may contain what is known as a look box 63, a small box with a glass wall through which the gasoline may be observed. 110

Water used as cooling medium in the apparatus is pumped from the bottom of the cooling tower through line 75 by a pump S into the main cold water line 16. This main cold water line connects by branch lines as described into the various coolers and condensers, and the hot water from them is fed back by branch lines to main hot water line 15 which discharges into the top of the cooling 115 tower T.

I have indicated in the foregoing description the nature of the various apparatus elements. Most of these elements need no further detailed description as they are well understood by those skilled in the art. For instance, the condensers, heat exchange or coolers, or heaters, separators, etc., will be well understood without detailed description. In fact, as to all these elements various forms 120 125 130

may be used, as is well understood. However, as to the absorption tower, evaporator, the final condensers and separator; and also as to the dephlegmator, consisting of reflux tower J and condenser or control section M, although various forms and arrangements may be used, I desire to describe more specifically the preferred form and arrangement of the devices I use in this system, and also to describe more in particular their operations and functions.

The details of the dephlegmator are shown in Figs. 4 and 6 to 9. In Fig. 4 the reflux tower portion of the dephlegmator is shown with a cylindrical shell 120 and with several superimposed floors 121 and 125. Although the detailed structure of the several superimposed floors may be varied, I show here a typical structure that will accomplish the operations desired in this system. For instance, the reflux tower J has several upper floors 121 with central openings surrounded by notched overflow rings 122; and each floor supports a pan bottom 123 peripherally surrounded by a notched overflow ring 124. The liquid that flows down through the reflux tower passes into the upper part of the tower through the tube 125^b into the first pan 123. Tube 125^b has a sealing cup 125^a at its lower end to prevent vapor passing up through it. Filling that pan and overflowing its notched edge it flows over onto the floor 121 directly below and, rising to a sufficient level on that floor, it overflows the inner notched ring 122 in that floor and flows down onto the next pan 123; and so on through the various floors. Where the liquid flows over the notched rings it is showered through the gases that are passed upwardly through the reflux tower, as will be hereinafter described.

Below the floors just described, there are several superimposed floors 125 that have a different type of apparatus for causing intimate admixture of the gases and liquids. This type of apparatus hereinafter briefly described is fully set forth and is the subject matter of the aforesaid application of Raymond B. Millard. A plan of one of the floors and its apparatus is shown in Fig. 6. Fig. 7 shows an enlarged detail cross section of some of the elements; and Fig. 8 shows some of the elements in perspective sectional detail. Each of the floors 125 extends around the inner periphery of shell 120 and is bounded at its inner edge by a vertical wall 126. In fact the floor 125 may be said to form only a ledge around the inside of the shell, interiorly bound by wall 126. Inside the wall 126 the gas and liquid admixing elements may be composed of upwardly facing channels 127 whose upwardly extending flanges 128 are spaced apart to provide spaces 129 through which the gases and vapors may flow upwardly. Over each pair of spaced channel flanges 128 there is an inverted chan-

nel 130 whose depending flanges 131 are spaced from flanges 128 so that the gas that flows upwardly between flanges 128 may flow over the upper edges of those flanges and downwardly through the spaces between flanges 131 and 128. Flanges 131 are provided with perforations 132 through which the gas and vapor may flow by depressing the liquid level to such a point as indicated at L in Fig. 7, the liquid level being depressed by the gas and vapor pressure so that the gases and vapors can pass through perforations 132 and bubble upwardly through the liquid that stands in the space between flanges 131, that liquid standing there at such a level as indicated at L¹. The liquid is fed into the liquid holding spaces by being dropped down above the inverted channel 130; and the liquid flows from each floor by passing out endwise from each space between flanges 131, through openings 133 in wall 126, these openings 133 registering with the spaces between flanges 131, as is indicated in Fig. 8. Both the channels 127 and 130 abut endwise against wall 126 and are welded or otherwise attached thereto so as to make a liquid tight joint therewith. The liquid that flows through openings 133 in wall 126 flows onto the floor 125 outside wall 126 and then, having risen to a sufficient level on floor 125, overflows the adjustable overflow collar 135 of overflow nipples 136 which direct the liquid downwardly into a trough 137 below the floor. Trough 137 below each floor is arranged in a direction lengthwise of the channels of that particular floor, as will be seen by noting the trough shown in dotted lines in Fig. 6. The trough 137 that takes the overflow from the floor above is, however, arranged crosswise of the channels of the floor immediately below (note the trough 137 shown in full lines in Fig. 6). Each trough may be provided with perforations in its bottom as shown at 138 in Fig. 6, and may also be provided with notches 139 along its edges as shown in Fig. 9. The trough, taking the liquid overflow from the floor above, distributes that liquid overflow equally to the central parts of all the channels of the floor next below; and the liquid thus distributed to the central parts of the channels flows outwardly towards the ends of the channels and then overflows into the trough next below to go to the floor next below. While passing through the channels the upwardly flowing gas and vapors bubble through the liquids and thus there is caused an intimate commingling of the gases and vapors and the liquids.

In the reflux tower here described this intimate commingling of the gases and vapors and the liquids is caused in two different manners; first, by causing the gases and vapors to bubble intimately through the liquids, and the other by causing the liquids to shower

down through the gases and vapors. Although the system here described is not necessarily limited to these particular details, yet I find that a reflux tower equipped in this manner is very efficient for the purposes herein set forth.

Condenser M directly above reflux tower J (condenser M and reflux tower J forming together the dephlegmator of the system) is of the same type as shown in Fig. 10, which is a showing of the final condenser N. Such a condenser is composed of cooling fluid tubes 140 extending across a vertical vapor passage 141, the ends of the tubes communicating with passages or compartments contained within cover plates 142. And these cover plates being provided with division walls 143 arranged so that the cooling water that enters by pipe 16^b first passes across through a certain number of tubes 140, enters a compartment 142^a in one of the cover plates, returns to compartment 142^b of the other cover plate through a certain number of tubes, then is turned back to compartment 142^c by certain other tubes, and so on, finally flowing through the last division of tubes into compartment 142^d and out through pipe 15^b. In such a condenser (I am describing this condenser as the condenser N, but its structure is the same as condenser M) the vapors and gases enter from above through pipe 50 and pass outwardly through the vertical vapor passage 141 of the condenser, the condensate and any uncondensed gases and vapors passing out from the condenser through pipe 51. In the condenser itself the vertical vapor passage is relatively large and free; and the condensate forms in small drops on the cooling tubes; and the space inside the condenser being relatively large and free there is little enforced commingling of the vapors and liquids. The vapors and gases flow quietly and slowly; there is little turbulence.

Assuming that condenser M of the dephlegmator is the same as condenser N shown in Fig. 10, it will be seen that the condensate from condenser M passes directly downwardly from that condenser through the vertical tube 145 into a compartment 146 in the upper end of reflux tower J. The uncondensed gases and vapors are fed to the reflux tower from evaporator I into the lower part of the reflux tower through pipe 34 (see Figs. 1 and 2) which pipe enters the reflux tower at the point 34^a (see Fig. 4) under the lowermost floor 125. The gases pass upwardly through the several floors and through the hereinbefore described apparatus, and finally the gases and vapors pass from the space above uppermost floor 121, out of the reflux tower and up through pipe 147 and into the top of condenser M. In this condenser M a definite control temperature (say 205°-210° F.) is maintained so that all the heavier constituents of the vapors are condensed while the

lighter vapor constituents are left in vapor state. In the vapors that reach the reflux tower there are, roughly speaking, three classes. First the vapors of what may be termed gasoline; second, the vapor of hydrocarbons lighter and more volatile than gasoline, and third, the vapors of hydrocarbons heavier and less volatile than gasoline, the last class consisting mainly of absorbing oil vapors. (There is also water vapor, but that may be for the moment ignored.) The temperature control in condenser M is maintained at such a point that the absorbing oil vapors are condensed while all the vapors of the two lighter classes are left uncondensed. The condensed and the uncondensed vapors and also whatever fixed gases there may be pass downwardly through condenser M and pass into upper chamber 146 of reflux tower J. In passing downwardly through the condenser there is a minimum of admixture of the vapors and liquids; the liquids gather on floor 146^a of chamber 146 and immediately flow downwardly through tube 125^b onto the uppermost floor 121. The uncondensed vapors in chamber 146 flow out from that chamber through pipe 50 to condenser N to be finally condensed.

But these vapors that finally flow out from chamber 146 are clear of all heavier condensate; and the heavier condensate that finally flows out from the bottom of reflux tower J is substantially clear of all lighter vapors owing to the action that takes place in the lower part of the reflux tower. The initial mixed vapors that enter at point 34^a at the lower end of the reflux tower are constantly passing up through and in intimate admixture with the downwardly flowing condensate, which condensate is at a temperature lower than the upwardly passing vapors. These upwardly passing vapors, which have not as yet been passed through condenser M, contain vapors of the heavier constituents as well as vapors of the lighter constituents. By contact with the cooler heavier condensate a certain amount of the heavier vapors are condensed as the mixed vapors pass up through the reflux tower. The mixed vapors being hotter than the heavy condensate, and being intimately admixed with that condensate, they pick up from the condensate any lighter vapors that may happen to be entrained in the downwardly flowing condensate. Thus if in condenser M any small portion of the lighter hydrocarbons happens to be condensed and mixed with the heavier condensate, the contact of the hotter mixed vapors will revaporize those lighter constituents and carry those lighter vapors up with the mixed vapors to the condenser M. Thus in the dephlegmator as I have described it, there may be a constant revaporization of certain constituents in the lower part of the reflux tower, those vapors passing up the condenser

70

75

80

85

90

95

100

105

110

115

120

125

130

and then a constant recondensation of those constituents to be passed downwardly into the lower part of the reflux tower as liquid, where they may again be revaporized. This constant circulation of vapors of a certain class, and the constant intimate admixture of the vapors and liquids, washing the lighter vapors out of the liquids and washing the heavier condensate mist out of the vapors, results in a very definite and clean separation of the heavier condensate from the lighter vapors, so that substantially nothing but vapors of the two lighter classes hereinbefore enumerated finally pass off from the dephlegmator through vapor pipe 50 to final condenser N, and substantially nothing but absorbing oil condensate finally flows off from the bottom of the tower.

The vapors that enter final condenser N through pipe 50 are those vapors of the two lighter classes, viz, vapors of what may be termed gasoline and vapors of hydrocarbons lighter than gasoline and which it is wished to separate from the gasoline; and water vapor. As these mixed vapors pass down through condenser N the gasoline and water vapors are condensed, the temperature in condenser N being maintained at a proper point (say 75° F.). As before stated, the vapor passage of condenser N is relatively large and open and as the vapors pass around cooling tubes 140 the condensate forms in small drops on the tubes, leaving the vapor passage relatively open and unobstructed; so that in the condenser there is relatively little enforced agitation and admixture of the condensate with the uncondensed vapors. As the condensate drops to the bottom of the vapor passage it flows off through pipe 51. This pipe 51 is made of sufficient size to carry off the condensate without filling the pipe to capacity so that the vapors that also pass down through the condenser and out through pipe 51 can pass out through the upper part of the pipe without being enforcedly admixed with the condensate. For this purpose pipe 51, as shown in detail in Fig. 10, is arranged with a horizontal run directly below condenser N and has no traps or pockets in it; so that the liquid can run off through the pipe at such a level as is indicated at L², and the vapors can flow through the same pipe above the liquid. Thus when liquid and vapors emerge into separator O the liquid may immediately drop down toward the bottom of the separator and the uncondensed vapors and gases may immediately rise without being intermingled with the liquid. In fact, as is shown best in Fig. 3, the entrance point of pipe 51 to the separator is very little above the level where the gasoline pipe 61 leads off from the separator, so that the liquid flowing from pipe 51 into the separator falls but a very little distance through the vapors standing above the liquid in the separator. The vapors then flow out of the upper end of the separator—through pipe 61^a and the gasoline through pipe 61, both the gases and liquids going separately to the gasoline tank R where the liquids stand in the bottom and the uncondensed vapors stand above the gasoline. As before stated, a back pressure valve 62 may be placed on gasoline tank R and this back pressure valve may be utilized to maintain on the whole system back to and including evaporator I, a suitable operating pressure, say 15 or 20 pounds per square inch above atmosphere. If the gasoline tank R is not capable of withstanding this pressure, valve 62 may be set at a lower pressure and back pressure valve 52 at the outlet of condenser N may be set to hold the desired pressure on the apparatus behind it. The advantage of holding a pressure on the gasoline tank R and of utilizing the uncondensed vapors to stand over the gasoline in that tank is that unnecessary evaporation of the gasoline is thus prevented and a considerable quantity of gasoline thus saved.

Going back further into the system for the purpose of explaining its process in general I note that absorption tower D is equipped with superimposed bubbling floors 125, similar in arrangement and construction to floors 125 described in connection with reflux tower J. Also evaporator I is equipped with similar superimposed floors 125. (Figs. 5, 6-9 may be taken to be details of the absorber and evaporator as well as of the reflux tower.) These floors are indicated in dotted lines in the absorber and evaporator in Fig. 1. In the absorber the action of the superimposed floors is to cause the upwardly flowing gas to be bubbled intimately through the downwardly flowing absorbing oil; the oil picking up all or substantially all of the gasoline carried by the gas. It is one of the features of operation of an absorption tower of this type and character that, operating at a certain controlled temperature (say 70° F.) it causes the absorbing oil to pick up practically all of the hydrocarbons condensable at that temperature, but a very small fraction of hydrocarbons that condense at a lower temperature. In other words the hydrocarbons picked up by the absorbing oil in the absorption tower are, in this particular instance, very purely gasoline, only a small percentage of lighter hydrocarbons being picked up. The vapor or gas pressure of the rich or laden absorbing oil is, therefore, comparatively low; and there is comparatively little of the very light vapors to be finally separated from the final gasoline condensate. The reasons for this action of the absorption tower are found in the facts that both the absorbing oil and the incoming vapor laden gases are cooled to a uniform absorption operating temperature before being put into the absorption tower; and also

in the fact that the gases and liquids are passed and re-passed many times into and out of contact with each other in their passages through the absorption tower. In other words, the gases are thoroughly washed in the absorbing oil many times over; and all hydrocarbons condensable at the operating temperature and pressure are absorbed by the oil, while practically all hydrocarbons vaporizable at the operating temperature and pressure are washed out of the oil by the gases. Any suitable pressure may be maintained on the bottom of the absorber. A pressure of about three pounds will operate such a tower, but in practice a pressure of about thirty pounds or more is actually used.

In weathering tank E, which is a simple tank in which the rich oil stands comparatively quiescent, any gases and very light vapors picked up by the oil have an opportunity of escaping at least to a certain extent; so that the laden oil that goes onto the heaters and to the evaporator carries a still lesser percentage of the lightest hydrocarbons to be finally separated by operation in condenser N and separator O.

In evaporator I, which is equipped also with floors 125, as before explained, the hot rich oil heated to the proper temperature in heater H and under a pressure say of about fifty pounds per square inch above atmosphere, has its pressure released to the lower pressure maintained by back pressure valve 52 or 62, with the result that the lighter hydrocarbons carried in the absorbing oil are vaporized almost completely. In practice, a pressure of five to twenty-five pounds gauge may be carried; but the pressure release to this lower pressure is not sudden but gradual, controlled by the gradual evaporation of the liquids and by the effect of the steam affecting the partial pressure.

All the vapors thus generated in the upper part of evaporator I pass immediately out of the evaporator through line 34 to the reflux tower. Due to the impossibility in practice of maintaining temperature and pressure conditions such as will in a single evaporation operation cause clean separation between vapors of lighter and heavier hydrocarbons, of course there is a small fraction of the absorbing oil also vaporized in the upper part of the evaporator; and so a small fraction of heavier vapors passes to the reflux tower along with the vapors of the lighter hydrocarbons, to be separated from the vapors of the lighter hydrocarbons, as before explained, by the action in the dephlegmator, of which the reflux tower forms a part. But in the evaporator not all of the lighter hydrocarbons will be immediately vaporized or will immediately pass off as vapors. The unvaporized heavy absorbing oil passes down through the evaporator, carrying with it any small unvaporized portion of the lighter hy-

drocarbons and also inevitably carrying down with it a small fraction of the lighter vapors which it entrains. These unvaporized absorbing oils then pass down through the various floors 125 of the evaporator and are met by the upwardly flowing water vapor from the steam introduced below; and also by the lighter vapors engendered by the heat of the steam and by the reduction of the partial pressure caused by the introduction of the steam into the liquid body below. Thus there are always hot vapors passing up through the evaporator and passing up through the downwardly flowing and cooler absorbing oil; and those vapors wash the absorbing oil of any entrained lighter hydrocarbon vapors; and also heat it so as to keep up its temperature to evaporate any lighter hydrocarbons that may be carried down in liquid form in the absorbing oil. And at the same time, the cooler absorbing oils wash out of the vapors any vapors or mist of heavy oil; making the vapors as clean as possible. Thus before the absorbing oil finally passes out of the evaporator, it is by reflux action and steaming entirely freed of all lighter hydrocarbon vapors, which lighter vapors join the lighter vapors passing out at the upper end of the evaporator. Thus in the evaporator all lighter hydrocarbons are entirely taken out of the absorbing oil so that the absorbing oil that then goes to the oil coolers to pass back to the absorption tower is entirely or substantially freed of lighter hydrocarbons it has picked up in the absorption tower.

To recapitulate briefly: It will be seen that in this system the original action in the absorbing tower is to the effect that the absorbing oil picks up from the original laden gas practically all of the hydrocarbons of a certain character and a minimum of hydrocarbons lighter than that. Then by the action of the system and particularly by the action in the evaporator, all of the lighter hydrocarbons are separated by evaporation from the absorbing oil, for this purpose a small part of the absorbing oil being also evaporated. Thus the absorbing oil is freed substantially entirely of its previously absorbed lighter hydrocarbons. Next the function and operation of the dephlegmator (reflux tower J and condenser M) is to entirely separate from the mixed vapors all the heavier hydrocarbons (the small percentage of absorbing oil vapors in the mixed vapors), leaving only the vapors of the desired hydrocarbons and a small proportion of still lighter hydrocarbons to go to the final condenser. Then the function and operation of the final condenser and separator is to separate cleanly the desired hydrocarbons, in form of a condensate, from the lightest hydrocarbons which are not desired in the final product.

I have spoken before of the fact that, in this system, as retention of a small amount

of absorbed hydrocarbons in the reflux absorbing oil does not affect the final efficiency of its gasoline recovery.

In general practice it is hydrocarbons that 5 freely vaporize at normal atmospheric temperature that are not desired in the final product. The desirable final product hydrocarbons, such as gasoline, do not freely vaporize at normal atmospheric temperature, but, of 10 course, have an appreciable vapor pressure at that temperature. At the operating temperatures and pressure indicated throughout the system as described, the final liquid product produced is one of the nature of gasoline; 15 while the final vaporous product separated from the gasoline is one that will not condense at normal atmospheric temperature. Consequently the final separated uncondensed vapor may be used to maintain a suitable vapor pressure over the final stored 20 gasoline to prevent slow evaporation of the gasoline, without the lighter vapors condensing into the gasoline in the storage tank.

From the foregoing description of the system in general, it will be seen that it has certain further advantageous features of operation. In so far as can be accomplished, the 25 heat of the system is kept within the system by heat interchange between relatively hot and cool fluid; and heat is supplied from the outside to the system only at evaporator I and heater H, which immediately precedes the evaporator; in other words, heat is supplied from the outside to the system only for the 30 purpose of evaporating the light hydrocarbons. The heat there supplied to the system is so transferred to the fluids and other parts of the system as to conserve the supply of heat as far as possible. For instance, the 35 hot lean oil passing away from evaporator I at a temperature of say 290° F. is first made to give up a part of its heat, in heat exchange G, to the rich oil that is passing to heater H. The rich oil going to heater H is thus pre- 40 liminarily warmed to as high a temperature as practicable (say about 240° F.) by taking heat away from the hot lean oil. The lean oil is thus cooled as much as practicable, so that the minimum amount of heat has to be 45 taken away from the lean oil by water cooling in cooler L, where the lean oil is cooled to approximately 70° F. for efficient operation in absorption tower D. The oil used in absorption tower D necessarily comes out at approximately 75° F. In order further to save 50 heat within the system, the cold rich oil flowing from pump F, instead of going directly through line 26 to heat exchanger G, may go through a line 70 to the line 16^b that feeds 55 condenser (control section) M with cooling fluid, and after being used in that condenser as a cooling fluid, and thus taking up a certain amount of heat, pass back through line 71, connecting with line 15^b, to heat ex- 60 changer G. Thus the temperature of the oil

entering heat exchanger G may be substantially higher than say 70° F., with the result that the rich oil is warmed to still higher temperature in the heat exchanger.

Another of the features of the apparatus as herein described is that it is capable of being arranged and mounted in a very compact arrangement on a single base, so as to be easily transported if desired. In oil field practice it is quite common that natural gas will be produced in comparatively large quantities in a given locality, but for only a short period of time. A portable absorbing system is, therefore, of much practical use. The system as here illustrated lends itself very readily to compact and portable arrangement, the whole system, with the exception of the cooling tower, the compressor, the absorber and the tanks, being mounted upon a single portable base. Such an arrangement is shown in 75 Figs. 2 to 5 inclusive.

Here is a suitable base, preferably made up of steel beams, illustrated at 90, and on it the various elements of the apparatus are mounted. In the plan of Fig. 2 heater H is shown mounted directly above the evaporator I which stands upon base 90. The gasoline and water separator O is shown mounted alongside evaporator I, with the look box 63 arranged in a convenient position and at a 80 convenient height alongside the evaporator. Gas cooler B is shown mounted on the base near one corner and directly above it is the gas scrubber B¹—and directly above that and mounted on the scrubber is the condenser N. At the same end, but at the other corner of the base is mounted the reflux tower J, with its condenser or temperature control unit M mounted directly above it. At the other side of the evaporator I from the reflux tower are mounted the oil cooler L and the heat exchanger G; and the various pumps are mounted in a line at the end of the base. Two water pumps S are provided so that either or both may be operated. They take cold water from the cooling tower through line 75 and pump it through main cold water line 16 from which various branch cold water lines run to the coolers and condensers as shown in Figs. 2 to 5, inclusive, the various branch lines being 90 there indicated by the same numerals as in Fig. 1. The hot water from the various coolers and condensers passes through the several branch lines indicated by numerals the same as in Fig. 1 to the main hot water line 15 (see 95 Figs. 2, 3 and 4) that is adapted at its upper end to be extended to the cooling tower.

The gas first enters the apparatus shown in Figs. 2 to 5 by entering scrubber B¹ at the flanged opening 100 of the scrubber. From the scrubber gas passes directly to the gas cooler B which is directly below the scrubber and then the gas passes out of the bottom of gas cooler B, through the pipe connection 11 to the absorbing tower which is not mounted 100

on the base with the rest of the apparatus. Below gas cooler B a drain 101 is shown to take drainage from the gas cooler (see Figs. 3 and 4 and corresponding diagrammatic showing on Fig. 1). From the absorption tower the gas, as before mentioned, passes off to mains or to storage as may be desired—the gas does not again enter the apparatus. The rich oil from the absorption tower, as before pointed out, goes next to the weathering tank which is also mounted independently of the unit assembled apparatus; and then from the weathering tank the rich oil goes to pump F. In Fig. 2 the entry of the cold rich oil from the weathering tank is shown through pipe 102 to pump F. From pump F the cold rich oil, as before described, goes through line 26 to heat exchange G; and pipe 26 leading from pump F to the heat exchange is also shown in Fig. 2. Figs. 2, 3 and 5 show the pipe 27 that leads the warm rich oil from heat exchange G to heater H; and from heater H the flow of the hot rich oil to evaporator I is through pipe 32 as shown in Figs. 2, 3 and 5. From the evaporator the vapors go through pipe 34 (shown only in Fig. 2) to the bottom of reflux tower J; and the final vapors from the reflux tower (after having been treated in the reflux tower as before described) go through pipe 50 (Figs. 2, 3, 4 and 5) to condenser N. Figs. 2 and 3 show best pipe 51, separator O, the pipe system 61, look box 63, etc., that take the condensate of condenser N and separate it and pass the gasoline through pipes 61 to the gasoline tank and the water through pipe 53 off to the water system before described.

From the reflux tower J the pipe 56 leads the condensed oils back to the oil system as before described (shown in Fig. 2). From evaporator I the hot lean oil goes by pipe 35 to heat exchange G, that pipe being shown in Figs. 2, 3 and 5; and the pipe 36 that takes lean oil from heat exchange G to pump K is shown in Fig. 2. From pump K the pipe 37 is shown in Figs. 2 and 3 going to oil cooler L; and from oil cooler L the pipe 20 that takes the cooled lean oil to the absorption tower is shown in Figs. 2, 3 and 5.

The various other details of apparatus elements and connective pipes are also shown on Figs. 2 to 5, indicated by their proper numerals, directions of flow being indicated by arrows, and legends being attached to indicate the various fluids flowing through the pipes; and all of this will be understood from what has previously been said in the description of Fig. 1. In Fig. 2 an additional pump Y is shown, and valve controlled pipe connections indicated generally by the numeral 110 are arranged so that the additional pump can be used as a substitute for either pump F or pump K. All of the pumps are connected to a common steam line 111, and steam lines 28 and 33^a are connected into steam line 111

to supply steam to heater H and evaporator I respectively. All the various pipes in the system are controlled by suitable valves, as will be readily understood without specific description of the valves.

70

I claim:

1. A process of recovering gasolines from natural gas, that includes absorbing from the gas and into a heavy absorbing oil all hydrocarbons condensable at a predetermined temperature, and during such absorption intimately commingling the gas and the absorbing oil and washing each in the other and thereby minimizing the absorption of hydrocarbons that normally condense at a temperature lower than said predetermined temperature, said gas and absorbing oil being maintained at approximately said predetermined temperature during the absorption operation; heating the laden absorbing oil and vaporizing its absorbed hydrocarbons and a portion of the absorbing oil, and thereby removing from the absorbing oil substantially all of its absorbed hydrocarbons; cooling and fractionally condensing the mixed vapors resultant from said evaporative action and thereby selectively condensing the absorbing oil vapors from said mixed vapors, returning the condensed absorbing oil to the main body of absorbing oil in the system after said absorbing oil has left the absorption operation and before it reaches the heating stage; and again cooling and fractionally condensing the resultant vapors to condense the gasoline vapors and leave the still lighter hydrocarbon vapors in vaporous form, said condensing action being carried on so that the gasoline condensate is not forcibly mixed with the uncondensed vapors; and firmly separating the condensate from the uncondensed vapors.

105

2. A process of recovering gasolines from natural gas, that includes absorbing from the gas and into a heavy absorbing oil all hydrocarbons condensable at a predetermined temperature, and during such absorption intimately commingling the gas and the absorbing oil and washing each in the other and thereby minimizing the absorption of hydrocarbons that normally condense at a temperature lower than said predetermined temperature, said gas and absorbing oil being maintained at approximately said predetermined temperature during the absorption operation, said absorption operation being carried on under pressure, then relieving the pressure on the laden absorbing oil without substantially changing its temperature and thereby releasing some of the vapors of the lighter absorbed hydrocarbons; and then heating the laden absorbing oil after the said pressure reduction thereof and vaporizing its absorbed hydrocarbons and a portion of the absorbing oil, and thereby removing from the absorbing oil substantially all of its absorbed

hydrocarbons; cooling and fractionally condensing the mixed vapors resultant from said evaporating action and thereby selectively condensing the absorbing oil vapors from said mixed vapors, returning the condensed absorbing oil to the main body of absorbing oil in the system after said absorbing oil has left the absorption operation; and again cooling and fractionally condensing the resultant vapors from said fractional condensing action, said condensing action being carried on so that the gasoline condensate is not forcibly mixed with the uncondensed vapors; and finally separating the condensate from the uncondensed vapors.

3. The process of recovering gasoline fractions from gas, that includes absorbing said fractions in comparatively heavy absorbing liquid; then heating the laden absorbing liquid to a temperature sufficient to vaporize the absorbed substances and also a portion of the absorbing liquid; then by fractional condensation separating substantially all the vapors of the absorbed liquid; and putting said absorbing liquid condensate back into the body of absorbing liquid in the process at a point subsequent to the absorption operation and before the heating stage.

In witness that I claim the foregoing I have hereunto subscribed my name this 24th day of July, 1926.

CLARENCE D. COULTER.

CERTIFICATE OF CORRECTION.

Patent No. 1,759,346.

Granted May 20, 1930, to

CLARENCE D. COULTER.

It is hereby certified that error appears in the printed specification of the above numbered patent requiring correction as follows: Page 10, line 104, claim 1, for the word "firmly" read "finally"; and that the said Letters Patent should be read with this correction therein that the same may conform to the record of the case in the Patent Office.

Signed and sealed this 22nd day of July, A. D. 1930.
